UNITED STATES PATENT OFFICE

HOWARD T. WALTON, OF COLLINGSWOOD, NEW JERSEY, ASSIGNOR TO DAVID LUPTON'S SONS COMPANY, OF PHILADELPHIA, PENNSYLVANIA, A CORPORATION OF PENNSYLVANIA

ADVERTISING DISPLAY DEVICE

Application filed May 26, 1931. Serial No. 540,053.

This invention relates to advertising display devices adapted for use on counters or in store windows; and it has reference more particularly to display devices of a box-like type enclosing lighting means to illuminate transparencies over side openings in the housings of the devices.

Considered from the broadest standpoint, my invention is directed toward the provision of an advertising device of the character referred to above, which is simple, compact and neat in appearance; which admits of the ready interchange of the transparencies without necessitating dismantling or disturbance of any of the parts at the interior; and which lends itself to very economic manufacture from sheet metal.

Other objects and advantages of this invention will be manifest from the detailed description following in coordination with the attached drawings, wherein Fig. I is an illustration partly in front elevation and partly in longitudinal section showing my improved advertising display device.

Fig. II is a fragmentary illustration of the device drawn to a larger scale with a portion thereof in plan, and another portion in horizontal section.

Fig. III is a cross section taken as indicated by the arrows III—III in Fig. I.

Fig. IV is a fragmentary rear view of a holder frame provided for the transparencies which are to be displayed.

Fig. V is a perspective view of a retaining means associated with the holder frame aforesaid; and

Fig. VI shows a fragmentary perspective view of a member forming a part of the housing of the device.

In the embodiment chosen for the purposes of illustration herein, the advertising display device of my invention comprises an elongate sheet metal housing 10, which, in cross section has the configuration of a trapezium, see Fig. III. The body portion of the housing constituting the top 11, back 12, and the bottom 13 is formed by angularly bending a rectangular blank of sheet metal along parallel lines in a manner which will be readily understood from Fig. III, with in-

cidental provision of a coextensive longitudinal opening 14 between downwardly and upwardly directed marginal portions 15, 16 of the blank at the front of the structure. The top and the bottom edges of the opening 14 are preferably finished off by retroversions of the metal of the body portion as at 17 and 18. The side walls 19 are suitably blanked to accurately fit within the ends of the body portion made as just explained, and provided, as shown in Figs. I and II, with plain inward flanges 20, 21 and 22 along those of its edges which correspond respectively to the top 11, back 12 and bottom 13 of the housing, to which latter the said flanges are permanently secured by riveting or welding. Within the height of the frontal opening 14, the forward edges of the side walls 19 are first retroverted as at 23 in Fig. II, and then bent laterally as at 24 to afford flanges whereof the purpose will be presently explained.

Angle strips 25, 26 secured respectively to the top 12 and bottom 13, in conjunction with the down and up turned portions 15, 16 set apart interiorly of the front of the housing 10, pockets 27, 28 for retainment of a holder frame 29 containing the transparencies which are to be displayed in the device. In this connection it is to be noted from Fig. II that the inward flanges 24 of the side walls 19 of the housing cooperate with the strips in the retention of the holder frame.

The hollow of the housing 10 behind the frame 29 is subdivided, by a series of spaced transverse partitions 30, into a number of chambers 31 each amply proportioned for the accommodation of an electric light bulb (not shown); and provisions in the form of louver openings 32 are made in the back of the housing for escape of the heat from the bulbs. For convenience in anchoring the conductor by which current is carried to the several electric light bulbs, the upright flange 26a of the strip 26 is cut at intervals along its length to provide tabs 26b, which, as shown in Fig. VI are adapted to be rolled down over the conductor C to hold it within the angle of said strip.

Referring now in detail to the holder frame

29, it will be observed from Figs. I, II and III, that the same is of a length to snugly fit the frontal opening 14 of the housing. The frame 29 is however of somewhat less height than the housing, so that by a slight lift, the upward projection 16 of the housing front may be cleared and the frame removed forwardly out of the opening 14 without entailing access to the interior of the said housing or disturbing the parts at the interior. By preference, the frame 29 is blanked integrally from stout sheet metal with perimetric top, bottom and opposite end rails 35, 36, 37 and 38, of right angle cross section, and a series of plain transverse bars 39 which correspond to the allocation of the subdividing partitions 30 within the housing and thus set apart a window 40 for each of the compartments 31. Angle strips 41 at the backs 20 of the transverse bars 39 of the frame 29 in conjunction with the lateral flanges of the perimetric rails 35-38 serve to confine glass lights 42, 43 in superposed pairs at the several windows of the frame, with interposition 25 of the transparencies whereof one is conventionally indicated at 44 in Figs. II and III. The function of securing each pair of the lights 42, 43 with capacity for ready removal from the frame 29 upon withdrawal 30 of the latter from the housing 10 to permit interchange of the transparencies, is vested in retainers 45, there being two such for each window. One of these retainers 45 is illustrated in perspective in Fig. V, and, as shown, 35 it is formed from a narrow strip of comparatively thin spring metal. At the lower end, the retainer has a short narrow central projection 46 between aligned shoulders 47, and at the top a somewhat longer narrow 40 tongue 48 between aligned shoulders 49. The retainers 45 are assembled with the frame 29 by insertion of their tongues 48 as far as permitted by the shoulders 49 into slots 50 of corresponding width in the lateral flange 45 35a of the top rail 35 of the said frame adjacent the opposite sides of the several windows 40 as exemplified in Figs. III and IV, and the tongues 48 are thereafter curled around the edge of the aforesaid flange as 50 at 51. The retainers are thus pivotally secured so that the projections 46 at their bottom ends may be sprung as far as permitted by the shoulders 57 into slots 52 of corresponding widths in the lateral flange 36a of the bottom perimetric rail of the frame. Incidentally, the retainers are bowed inwards to yieldingly engage the innermost of the glass lights 42, 43 and thereby hold them in 55 position against displacement and rattling. Removal of the retainers 45 is effected in the reverse manner, i. e., by bowing them outward to release the projections 46 from the slots 52. For convenience in removing the holder frame 35, the latter is fitted with graps han-

dles 53 which are secured to certain of the cross bars 39, see Figs. I and III.

Having thus described my invention, I claim:

1. An advertising display device comprising a housing adapted to accommodate illuminating means, and having an opening in its front closed by a withdrawable frame; a glass backed transparency fitting the frame; and means to removably retain the glass against displacement and rattle in the frame, the said means being in the form of a bow spring pivotally connected at one end to a bar of the frame and having shouldered projections at their opposite ends adapted to engage in apertures of corresponding size in the opposite bar of the frame. 70

2. An advertising display device comprising a housing adapted to accommodate illuminating means, and having an opening in its front closed by a removable frame; a glass backed transparency fitting the hollow of the frame; and means to removably retain the glass against displacement and rattling within the frame, the said means having the form of bow springs with one of their ends pivotally engaging in one bar of the frame and their opposite end formed with shouldered projections to slip into apertures of corresponding size in an opposite bar of the frame. 85

3. An advertising display device comprising a housing adapted to accommodate illuminating means, and having an opening in its front closed by a removable frame; and an angle strip within the housing engaging said frame and having one of its flanges cut with provision of straps at intervals adapted to be curled about a conductor supplying current to the illuminating means for the purpose of anchoring such conductor within the angle of the strip. 100

4. A device of the character described comprising a metal sheet bent to form the bottom, back, and top of an illuminant housing of trapezoidal cross section, with upturned and downturned flanges at the front edges of said bottom and top affording a front opening between them and adapted to retain a transparency frame behind them; end walls for said housing with shoulders behind their front edges affording open-fronted seats for a transparency frame; and a transparency frame in the front of the housing seated against said shoulders and normally engaged behind said flanges, but removable by mere vertical shifting to free one of its horizontal edges and permit it to be first swung forward and then again shifted vertically. 110

5. A device of the character described comprising a metal sheet bent to form the bottom, back, and top of an illuminant housing of trapezoidal cross section, with upturned and downturned flanges at the front edges of 125

said bottom and top affording a front opening between them and adapted to retain a transparency frame behind them; end walls for said housing adapted to receive a transparency frame between them and without impediment to its subsequent removal; internal longitudinal angles on the bottom and top walls of said housing with flanges affording shoulders paralleling the aforesaid top and bottom flanges; and a transparency frame in the front of the housing seated against said shoulders and normally engaged behind said flanges, but removable by mere vertical shifting to free one of its horizontal edges and permit it to be first swung forward and then again shifted vertically.

In testimony whereof, I have hereunto signed my name at Philadelphia, Pennsylvania, this 22nd day of May, 1931.

20 HOWARD T. WALTON.
